UNITED STATES PATENT OFFICE.

THEODORE F. RANDOLPH, OF CINCINNATI, OHIO.

COMPASS-BOX.

SPECIFICATION forming part of Letters Patent No. 284,331, dated November 9, 1880.

Application filed August 30, 1880. (No model.)

To all whom it may concern:

Be it known that I, THEODORE F. RANDOLPH, of Cincinnati, Hamilton county, Ohio, have invented certain new and useful Improvements in Compass-Boxes, of which the following is a specification.

My invention comprises a light, cheap, durable, and jointless box, within which a surveyor's compass can be securely housed, so as to be readily carried about from place to place without danger of being broken or otherwise injured, the peculiar construction of said seamless box being hereinafter more fully described, and pointed out in the claims.

15 In the annexed drawings, Figure 1 is a plan view, showing my box in its open position. Fig. 2 is an enlarged vertical section of the same in its closed condition. Fig. 3 is a greatly enlarged section of a portion of the body of the box.

The bottom A and the four sides B of the lower portion or body of the box are constructed without seams or other joints, as they are all composed of a single piece of heavy 25 leather, which is first soaked in water or otherwise rendered soft and pliable, and after being thus softened said leather is placed in a die or mold and subjected to the action of a plunger or follower. This plunger forces the leather 30 into the die and retains it there until the leather has had time to set and become hard and stiff. The plunger is then retracted and the leather withdrawn from the mold, the leather being now free from seams or joints or any 35 sharp angles, and the vertical corners of the same being rounded very considerably, as shown at b in Fig. 1. Another piece of leather, made in precisely the same manner, serves as the seamless lid or cover of the box, C being 40 the top, D the vertical sides, and d the rounded corners, of said lid. E E' are hinges or straps wherewith this lid is coupled to the body A B, said body having secured to its upper margin a valance, F, which conceals the parting of 45 these two members A B and C D.

Securely fitted within the body A B is a block, G, having a central circular pit, H, to receive the compass, it being understood that the box herein represented has been designed 50 more especially to contain an instrument similar to the one described in the patent issued to me June 24, 1879. Located at the front corners of the box are two other blocks, I I',

having turn-buttons J J', that retain in position the compass and its accessories, such as 55 the telescope, &c.

K is a stump, over which is sprung the shade-tube L of the telescope.

Depending from the top C is a block, N, that terminates with a cone, O, the latter being 60 adapted to enter the ball-socket in the under side of the compass, the instrument being inverted when placed in the box, so as to protect the glass and thereby obviate the necessity of a special cover for the same. 65

P is a strap, and R a buckle, that maintain the lid in a closed condition. S is a strap or other suspender, wherewith the box can be readily slung around a person's shoulder or attached to a saddle. 70

Whatever size this box may be made it is evident it combines the advantages of lightness, strength, durability, and cheapness, as it cannot warp nor split, neither can it be broken by a fall, as there are no seams or 75 nailed joints to come apart. Furthermore, the comparatively elastic nature of the leather prevents the instrument being injured, no matter how roughly the box may be handled.

My invention may be modified by cementing together two or more thin pieces of leather and then pressing them in a die, so as to cause them to become practically a single piece. 80

I claim as my invention—

1. A seamless compass-box consisting of a 85 body whose bottom A and sides B are formed out of a single piece of pliable material pressed into the desired shape, said body being stiffened with a block, G, provided with a pit, H, to receive the instrument, a lid, C D, of similar construction to the body, being hinged to the latter, and having a projection, O, that enters the compass-socket when said lid is closed, as herein described. 90

2. A seamless compass-box consisting of 95 the body A B and hinged lid C D, constructed as above described, said body being provided with a pitted block, G H, and turn-buttons J J', and said lid being furnished with a projection, O, as herein described. 100

In testimony of which invention I hereunto set my hand.

THEODORE F. RANDOLPH.
